[57] **CLAIM**

The ornamental design of a telephone stand, as shown and described.

DESCRIPTION

FIG. 1 is a top, front and right side perspective view of a telephone stand showing our new design;

FIG. 2 is a top plan view thereof;

FIG. 3 is a bottom plan view thereof;

FIG. 4 is a front elevation thereof;

FIG. 5 is a right side elevation thereof;

FIG. 6 is a left side elevation thereof;

FIG. 7 is a rear elevation thereof; and,

FIG. 8 is a top plan view of a modified embodiment of the design shown in FIGS. 1 through 7.

The modified embodiment shown in FIG. 8 is the same in appearance as the embodiment shown in FIGS. 1 through 7 except for the configuration of the buttons and display screen as shown in FIG. 8.

1 Claim, 4 Drawing Sheets
